UNITED STATES PATENT OFFICE.

JOHN A. TAYLOR, OF PICABO, IDAHO, ASSIGNOR OF ONE-HALF TO JOHN H. CARPENTER,
OF PICABO, IDAHO.

RECOIL-OPERATED FIREARM.

1,078,224.

Specification of Letters Patent.

Patented Nov. 11, 1913.

Application filed November 5, 1912. Serial No. 729,680.

To all whom it may concern:

Be it known that I, JOHN A. TAYLOR, a citizen of the United States, residing at Picabo, in the county of Blaine, State of Idaho, have invented certain new and useful Improvements in Recoil-Operated Firearms; and I do hereby declare the following to be a full, clear, and exact description of the invention, such as will enable others skilled in the art to which it appertains to make and use the same.

This invention relates to recoil operated firearms.

The object of the invention resides in the provision of an improved construction of firearm wherein the operations of opening the breech after firing a shot, extracting and ejecting the empty cartridge shells, cocking the firing hammer, introducing a fresh cartridge into the ammunition chamber, and closing and locking the breech, are automatically effected by the recoil incident to firing and the reaction of the recoil spring.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a side elevation of a firearm constructed in accordance with the invention. Fig. 2 a view similar to Fig. 1 with the mechanism cover plate removed and the parts of the mechanism shown in firing position, the handle in this view being partly in section to disclose the latch for securing the magazine therein. Fig. 3 a view similar to Fig. 2 showing the parts of the mechanism in the position they would occupy after firing, the breech block being recoiled. Fig. 4 a view similar to Fig. 2 showing the safety mechanism in active position. Fig. 5 a vertical section through the rear portion of the firearm with the parts in firing position.

Fig. 6 a plan view partially in section with the breech block in closed position. Fig. 7 a view similar to Fig. 6 showing the rear portion of the firearm with the breech block recoiled. Fig. 8 a partial side elevation looking at the rear portion of the right hand side of the firearm and showing the breech

block catch in unlocked position. Fig. 9 a view similar to Fig. 8 showing the breech block catch in locked position. Fig. 10 a detail perspective view of the trigger of the mechanism, the sliding and pivoted sections of the trigger being separated. Fig. 11 a rear elevation of the firearm. Fig. 12 a view similar to Fig. 5 showing the breech block partly recoiled. Fig. 13 a view similar to Fig. 5 showing the breech block fully recoiled. Fig. 14 a detail perspective view of the extractor. Fig. 15 a detail perspective view of the breech block. Fig. 16 a detail perspective view of the safety slide. Fig. 17 a view similar to Fig. 2 partly broken away and partly in section to better disclose certain parts of the breech mechanism, and Fig. 18 is a section on the line 18—18 of Fig. 3.

Referring to the drawings the invention is shown as comprising a barrel A which terminates at one end in a receiver B from which latter depends the handle C. The receiver B is provided with a breech chamber 20 opening through the upper side of said receiver and communicating with the bore of the barrel A and also with a magazine receiving passage 21 formed in the handle C. Slidably mounted in the chamber 20 for longitudinal movement is a breech block E which is of skeleton formation. This breech block is provided adjacent its forward end with a transverse partition 22 and between this partition and the forward end the breech block is provided with side and bottom walls, the left hand side wall of said block being provided with a slot 23 for a purpose that will hereinafter appear. The bottom wall of the breech block E is provided with a longitudinal groove 24 which opens through the forward end of said breech block. The top of the breech block is provided with a longitudinal recess 25 which extends partly into the closed front end of the breech block. Mounted within the breech block E between the rear end thereof and the partition 22 is a rod 26 encircled by a recoil spring 27 one end of which bears against the partition 22, while the other end thereof bears against a projection 28 formed on a block 29 fixedly secured to the receiver B, said projection 28 being provided with an opening 30 through which the rod 26 is adapted to slide. By this construction it will be apparent that the spring 27 will constantly tend to move the breech block E to closed position and that the retraction of

said breech block will result in the spring 27 being compressed. The end of the rod 26 adjacent the partition 22 is provided with a longitudinal recess 31 in which is slidably mounted a firing pin stem 32 the forward end of which is enlarged and provided with a firing pin point 33 adapted to pass through an opening 34 in the front end of the breech block and engage the primer of a cartridge disposed in the ammunition chamber of the barrel A. The firing pin stem 32 is enlarged laterally between the partition 22 and the front end of the breech block and this enlarged portion of said stem extends through the slot 23 and is provided with a shoulder 35 for a purpose that will hereinafter appear. Pivotaly mounted in the recess 25 is an extractor arm 36 the forward end of which is provided with a nib 37 adapted to engage over the rim of a cartridge when the breech block is closed so that when the breech block is retracted the extractor arm will effect the withdrawal of the empty shells from the ammunition chamber of the barrel. Seated in the recess 25 is a spring 38 which constantly bears against the inner end of the extractor arm 36 and serves to maintain the nib 37 in operative engagement with the rim of a cartridge. The nib 37 is provided with a beveled face which rides over the rim of cartridge during the closing of the breech block and allows the nib to pass into engagement with the cartridge rim. Encircling the firing pin stem 32 and having one end bearing against the enlarged portion of said stem and its other end bearing against the partition 22 is a firing pin spring 39.

Secured to the handle C and the receiver B is a trigger guard 40 within which is slidably mounted a trigger 41 normally held at the limit of its forward movement by a spring 42 interposed between the end of the trigger and the adjacent face of the handle. Formed on the trigger 41 is an upwardly extending ear 42' to which is pivotally connected an ear 43 formed on a sear tripping plate 44, said plate 44 being provided on its upper side with a sear engaging shoulder 45. Formed on the plate 44 and projecting from the end thercof remote from the ear 43 is a finger 46 adapted for engagement with a curved face 47' formed on the breech block E during the movement of the breech block so as to hold the plate 44 out of sear engaging position against the influence of a spring 47 interposed between the trigger 41 and the plate 44 near the pivoted end of the latter. It will be here noted that the receiver B is recessed on its left hand side just above the trigger 41 to receive the plate 44 and other mechanism to be hereinafter referred to and it will also be noted that this recess is sufficiently deep to afford communication between the same and the recess

in which the breech block E slides so as to permit certain parts of the mechanism to operate in said lateral recess and also in the recess wherein the breech block reciprocates.

Pivotaly mounted in the lateral recess 70 of the receiver B above the plate 44 is a sear 48 in the form of an angle lever and having one arm thereof provided with a shoulder 49 adapted for coöperation with the shoulder 45, while the free end of the other arm of said sear projects in the recess 20 and is adapted to coöperate with the shoulder 35 on the firing pin stem to effect the cocking of the firing pin upon the return of the breech block E to closed position under the influence of the recoil spring 27. The sear 48 is normally held in position to coöperate with the shoulder 35 by means of a spring 50 interposed between a fixed part of the receiver and the inner face of the arm of 80 said sear which is disposed in the lateral recess of said receiver.

The plate 44 is provided on its lower side with a recess 51 between the side walls of which is mounted a rod 52 and upon this 90 rod is slidably mounted a block 53 provided with a locking lip 54 on the end thereof adjacent the free end of the plate 44. The block 53 is normally held at the limit of its movement toward the free end of the plate 95 44 by a spring 55 which encircles the rod 52 and has one end in engagement with the side wall of the recess 51 and its other end in engagement with the block 53.

Formed on the receiver B and projecting 100 into the lateral recess of said receiver is a lip 56 beneath which the lip 54 of the block 53 is adapted to engage under predetermined conditions to hold the plate 44 against movement to sear engaging position under the 105 influence of the spring 47. The mechanism just described is confined within the lateral recess of the receiver by a cover plate 57 which may be readily removed when desired so as to afford access to the mechanism contained in the lateral recess of the receiver.

Formed in the left hand side of the receiver B is a longitudinal groove 58 one end of which communicates with the lateral recess of said receiver. Mounted for movement in the groove 58 is a safety slide 59 which is provided on the inner face of its forward end with a lug 60 having a beveled edge 61 adapted for coöperation with a beveled edge 62 formed on the free end of the 120 plate 44. The rear end of the slide is provided with an inwardly projecting pin 63 which is adapted to spring into a recess 64 formed in the bottom of the groove 58 whereby said slide is locked against accidental movement from inactive to active position. The slide 59 is further provided at its rear end with a thumb piece 64' whereby the same may be conveniently operated with the fingers. Mounted in the passage 125 130

21 of the handle C is a magazine casing 65 in which is disposed the usual feed spring 66 and follower plate 67, the action of said spring and follower plate being such as to 5 constantly tend to move cartridges loaded in the magazine casing upwardly. The casing 65 is normally held against disengagement from the passage 21 by means of a spring controlled latch 68 which is adapted 10 to engage over a projection 69 formed on said casing 65.

Mounted in the receiver B in the bottom of the recess 20 is a pin 70 which projects into the groove 24 of the breech block and 15 overlies the rear side of the passage 21, said pin having the function of holding the loaded cartridges in the magazine and of also effecting the ejection of the empty cartridge shell upwardly through the recess 20 during 20 the final retractive movement of the breech block after firing. The rear end of the receiver B is provided with a recess 71 in which is pivotally mounted a latch 72 provided with a lip 73. Mounted in the recess 25 71 is a spring 74 which serves to lock the latch 72 in either active or inactive position. In the active position of the latch 72 the lip 73 is adapted to engage in a recess 75 formed in the rear end of the breech block E and 30 whereby said block is locked against accidental retraction.

Assuming the parts to be in the position shown in Figs. 2 and 17 the operation of the firearm upon firing will be as follows. By 35 pulling the trigger 41 rearwardly against the influence of the spring 42 the plate 44 will likewise be drawn rearwardly and this movement of the plate 44 will cause the shoulder 45 to engage the shoulder 49 of the sear 48 and rock said sear so as to disengage the same from the shoulder 35 of the firing pin thereby releasing the firing pin to the influence of the spring 39. The firing pin will then be moved forward and 40 fire the cartridge disposed in the ammunition chamber of the barrel A. The recoil resulting from the firing of the cartridge will react upon the breech block E and retract the latter against the influence of the 45 recoil spring 27. During the retraction of the breech block E the extractor arm 37 will draw the empty cartridge shell rearwardly until said shell comes sharply into engagement with the pin 70 when it will be thrown 50 upwardly out of the recess 20. During this retraction of the breech block the finger 46 will engage the curved face 47' of the breech block and as a result thereof said finger and the plate 44 will be forced downwardly so 55 as to withdraw the shoulder 45 from engagement with the shoulder 49 of the sear and allow the latter to be operated by the 60 spring 50 to a position for engagement with

the shoulder 35 as the breech block is returned to closed position by the spring 27. 65 This return movement of the breech block under the influence of the spring 27 will force the uppermost cartridge in the magazine into the ammunition chamber of the barrel and as previously stated will bring 70 the shoulder 35 into engagement with the sear 48 and thus automatically cock the firing pin. This operation is repeated each time the firearm is discharged. As the trigger 41 is drawn rearwardly against the influence of the spring 42 the lip 54 of the block 53 will ride over the beveled forward end of the projection 56 and upon the retraction of the breech block the downward movement of the plate 44 as a result of the 80 co-operation of the finger 46 with the curved face 47' will cause the block 53 to move inwardly of the plate 44 against the influence of the spring 55. As soon as the lip 54 of the block 53 has passed beneath the projection 56 the spring 55 will operate to engage the lip 54 beneath said projection 56 and in this manner the plate 44 will be locked 85 against upward movement into operative relation with the sear 48 until pressure on the 90 trigger 41 is entirely removed.

In order to lock the mechanism against firing it is only necessary to operate the slide 59 forwardly of the firearm when the beveled edge 61 of the lug 60 will engage 95 the beveled edge 62 of the plate 44 and thus force said plate 44 downwardly out of operative relation with respect to the sear 48. With the plate 44 held in this position by the operation of safety slide it will be apparent that the rearward movement of the trigger 41 and the plate 44 will not disengage the sear 48 from the shoulder 35.

What I claim is:—

In an automatic firearm, the combination 105 of a receiver, a breech block slidable in the receiver, said block having a hollow interior opening through its side walls and bottom, a partition dividing the interior of the block into front and rear chambers, a longitudinal 110 rod in the rear chamber having in its forward end an opening coinciding with an opening through the partition, a firing pin 115 slidable in said openings, spring means constantly tending to move said pin to firing position, a lateral projection on said pin extending through the side wall of the block, and a sear on the receiver for engaging said projection during counter recoil to move the firing pin to retracted position. 120

In testimony whereof, I affix my signature in the presence of two witnesses.

JOHN A. TAYLOR.
